UNITED STATES PATENT OFFICE.

PETER E. WHITSON AND ORREN G. NOSKER, OF SHELDON, ILLINOIS.

DESIGN FOR A BROOM-RACK.

SPECIFICATION forming part of Design No. 21,708, dated July 12, 1892.

Application filed June 13, 1892. Serial No. 436,587. Term of patent 14 years.

To all whom it may concern:

Be it known that we, PETER E. WHITSON and ORREN G. NOSKER, citizens of the United States, residing at Sheldon, in the county of 5 Iroquois, State of Illinois, have invented a certain new and useful Design in Broom-Racks, of which the following is a specification, reference being had therein to the accompanying drawing.

10 The drawing represents a perspective view of our design.

The leading feature of our design consists of a rack having substantially inverted-V-shaped outline.

15 A is the rack or support which in its gen-

eral contour resembles an inverted V. Upon one or both sides of the inclined portions are represented spaces B for advertising matter. At or near the apex is open-work, as shown at C.

What we claim is—

20 The design for a show-rack, substantially as herein shown and described.

In testimony whereof we affix our signatures in presence of two witnesses.

PETER E. WHITSON.
ORREN G. NOSKER.
